ROLLING MILL

John J. Eckfeldt, Chicago Heights, Ill., and Nels E. Flodin and Frank A. Lawson, Latrobe, Pa.; Emma B. Eckfeldt executrix of said John J. Eckfeldt, deceased; assignors to American Locomotive Company, New York, N. Y., a corporation of New York

Application December 1, 1934, Serial No. 755,526

21 Claims. (Cl. 80—5)

This invention relates in general to rolling mills and has particular reference to a rolling mill designed for the rolling of a circular bloom into a rolled ring having an interior circumferential collar or web.

A principal object of this invention is to provide a mill of the character described embodying an improved roll mechanism for efficiently forming the interior circumferential web of the rolled ring.

A further object is to provide a mill of the character described embodying improved roll mechanism for forming the interior circumferential web of the rolled ring, which mechanism is so designed as to be easily and speedily adjustable from an engaged operating position to a disengaged open position and vice versa, whereby a rolled ring may be removed from the mill and a fresh bloom inserted in position for rolling with a minimum expenditure of time and effort.

Other objects of and advantages achieved by this invention will be apparent from the following description when considered in connection with the accompanying drawings which illustrate a present preferred embodiment of the invention and certain modifications of parts thereof.

In the accompanying drawings Figure 1 is a longitudinal vertical sectional view on the line I—I of Fig. 2 of a rolling mill embodying the invention in the present preferred form thereof, certain parts being broken away and certain parts being omitted; Fig. 2 is a plan view on the scale of Fig. 1 of the rolling mill of Fig. 1, certain parts being shown in section on the line II—II of Fig. 3 and certain parts being omitted; Fig. 3 is an enlarged section on the line III—III of Fig. 2, certain parts being omitted; Fig. 4 is a section on the line IV—IV of Fig. 3, certain parts being broken away; Fig. 5 is a plan view of the structure shown in Fig. 3; Fig. 6 is a section on the line VI—VI of Fig. 3 of the lower part of the carriage; Fig. 7 is an enlarged fragmentary plan view partly in section showing one of the guide rolls and its adjustable bearing means; Fig. 8 is an end view of the parts shown in Fig. 7; Fig. 9 is an elevation, with certain parts in section and certain parts being broken away, of a modified construction of the web-forming rolls; and Fig. 10 is a similar view of another modified construction of the web-forming rolls.

For the purpose of illustrating this invention there is shown in the drawings so much of a rolling mill as is necessary for the proper understanding of the invention. The improvements comprising the present invention are applicable

to various types of rolling mills. In the present instance however, it is illustrated in connection with a mill of the type disclosed in U. S. Patent No. 949,279, to J. Kennedy, issued February 15, 1910, and in its association with the principles 5 of the mill of the patent provides an improved mill which not only retains all of the structural advantages and methods of operation of the mill of the patent but in addition thereto possesses certain advantages which will later appear. Those 10 parts of the mill shown in the drawings not forming a part of the novel features of this invention will now be briefly described prior to the detailed description of the novel features of this invention.

A ring or bloom 1 is shown in Figs. 1 and 2 in position being rolled into a finished ring in the rolling mill. The rolling mill comprises a main roll 2 which operates on the exterior surface of the ring 1 and is mounted on a vertical shaft 20 3 which shaft is suitably journaled in bearings 4 provided in the frame of the mill indicated generally by the numeral 5. The shaft 3 is power driven through connections including a bevel gear 6 secured on the shaft, a bevel pinion 7 in mesh 25 with the gear 6, a horizontal shaft 8 on one end of which the pinion 7 is secured, and a gear wheel 9 secured on the other end of the shaft 8. Suitable bearings 8a, supported on the frame 5, are provided for the shaft 8. A gear wheel 10 is secured on a hollow extension 11a, hereinafter further described, of a power driven shaft 11 and is in mesh with the gear wheel 9. The main roll 2 is thus power driven by the shaft 11. It will be understood however that the power may, and 30 in some instances preferably will, be applied directly to the shaft 8 at its end indicated at 8b.

A carriage for the web-forming roll mechanism of this invention hereinafter described in detail, indicated generally by the numeral 12, is disposed 40 at the left side of the roll 2 as viewed in Figs. 1 and 2. The carriage comprises an upper frame unit and a lower frame unit (features of the present invention) which are connected as hereinafter described. The lower unit is connected 45 with four horizontal rods or long bolts 13 which extend toward the right end of the mill and are secured at this end to a crosshead 14. Sleeves 15 are provided around the rods for holding the carriage and crosshead apart. The upper part 50 of the crosshead is secured to a main plunger 16 of a single-acting hydraulic cylinder 17. The axis of the cylinder 17 (see Fig. 2) is in line with the axis of the roll 2 and shaft 3 and when liquid under pressure is admitted to the cylinder 17 55

the plunger 16 is forced to the right and the carriage 12 and the roll mechanism carried thereby is thereby pulled toward the stationary roll 2, the carriage sliding on suitable guide members on which the lower frame unit is mounted, which members are a part of the frame 5 of the mill, as clearly shown in Fig. 3.

A push-back plunger 18 is secured below the plunger 16 to the crosshead 14 and extends longitudinally therefrom toward the right end of the mill. The plunger 18 moves in a single-acting hydraulic cylinder 19 to which liquid under pressure is constantly applied so that the plunger will act, through the connecting parts, to force the crosshead 14 and hence the carriage 12 and mechanism carried thereby away from the roll 2 whenever pressure is released from the main cylinder 17. The cylinder 17 is of course adapted to provide substantially greater power than the cylinder 19 so that when the plunger 16 is moved to the right it will readily overcome the force of the plunger 18.

Two guide rolls 20 (see Fig. 2) are disposed so as to bear on the exterior of the bloom at the sides of the roll 2 and the roll mechanism carried by the carriage 12. Each of the rolls 20 is journaled in a bearing on the end of one arm of a bell crank lever 21. The levers 21 are pivoted as indicated at 22 to parts of the frame 5. The other arm of each bell crank lever is pivotally connected to a rod 23 which rod is in turn pivotally connected to a crosshead 24 at the right end of the mill.

The crosshead 24 is secured to a plunger 25 of a single-acting hydraulic cylinder 26 having its axis in alignment with the axis of the cylinder 17. A stationary plunger 27 is secured to the right end of a stem 28 which stem extends through the cylinder 17 and plunger 16 and is secured to the head of the cylinder 17 at the left end thereof. A hydraulic cylinder cavity 29 is formed in the left end of the plunger 25 into which cavity the right end of the plunger 27 extends.

Liquid under pressure is constantly supplied through a suitable port 27a formed in the plunger 27 to the interior of the cavity 29 so that whenever pressure is released in the cylinder 26 the plunger 25 will be forced back (to the right) and through the connecting mechanism will move the bell crank levers 21 so as to release the guide rolls 20 from the bloom or ring being rolled. The cylinder 26 is of course adapted to provide substantially greater power than the cavity 29 so that the plunger 25 will be readily forced to the left overcoming the power provided by the cavity 29 when fluid under pressure is supplied to the cylinder 26 and the guide rolls 20 may be thereby adjusted to various positions so as to aid in the attainment of the desired shape of the bloom.

The cylinders 17 and 26 are suitably bolted at their lower portions to the frame 5 and are connected at their upper portions by long bolts 30 which extend through lugs formed on these cylinders, sleeves 31 being provided around the bolts 30 between the lugs for holding them properly spaced apart.

A stop consisting of a nut 32 in threaded engagement with the stem 28 is provided for limiting the movement of the plunger 16 toward the right and hence the movement of the carriage 12 toward the roll 2. A worm shaft 33 is mounted in suitable bearings on the frame 5 and extends over the nut and meshes with teeth formed cir-

cumferentially in the nut. Hand wheels 34 are provided on the opposite ends of the shaft 33 so that by turning these wheels the nut may be regulated to adjust the throw of the plunger 16 and consequently the final position of the carriage 12.

Lower and upper edging rolls 35 and 36 respectively are provided for operation on the edges of the bloom. The roll 35 is carried on the right end of a shaft 37 which is mounted in suitable bearings 38 and 39. The bearing 38 is movable longitudinally of the mill as will presently appear and the bearing 39 is fixed against longitudinal movement.

The bearing 39 comprises a coupling which is screwed onto the hollow extension 11a of the shaft 11 hereinbefore mentioned. The extension 11a is mounted in a bearing 40 carried on the frame 5. The shaft 37 is splined to the bearing 38 and extension 11a as indicated at 41 so that the shaft 37 and consequently the roll 35 will be positively rotated with the shaft 11 while the shaft 37 may be moved axially thereof, that is to say longitudinally of the mill. The left end of the bearing 39 is formed as a gear wheel 42 for a purpose hereinafter explained.

The bearing 38 is carried on a frame 43 which is movable longitudinally of the mill within suitable guides (not shown) carried on the frame 5. Movement of the frame 43 is effected by piston rods 44 which connect the frame 43 with pistons (not shown) which pistons operate in hydraulic double-acting cylinders 45 mounted one at each side of the frame 5 at the left end thereof. The longitudinal positioning of the rolls 35 and 36 is thereby controlled to accommodate blooms of different sizes.

The roll 36 is carried on the right end of a shaft 46 which shaft is pivotally connected to the frame 43 by a suitable coupling indicated at 47 and extends through a bearing 48 which is disposed adjacent the roll 36. An upwardly extending pitman 49 is carried in a socket 49a formed in the top of the bearing 48. A hydraulic cylinder 50 is carried on the frame 43 above the bearing 48. A plunger 51 operates in the cylinder 50. A socket 52 is provided in the lower end of the plunger 51 within which socket the pitman 49 bears against the plunger. Introduction of liquid under pressure into the cylinder 50 serves to force the roller 36 down onto the edge of the bloom. A stem 51a extends upwardly from the plunger 51 through a stuffing box 50a in the top of the cylinder. The stem is squared at its upper end and screw-threaded adjacent its squared portion. An adjusting nut 51b and a lock nut 51c are provided on the screw-threaded portion. The nut 51b strikes against an upwardly extending portion on the stuffing box 50a to limit the downward movement of the stem 51a and consequently the downward forcing of the roll 36. Adjustment of the nut 51b will obviously adjust the limit of downward forcing of the roll 36 so that blooms of varying thicknesses can be accommodated. It will of course be understood that any other suitable means for determining the limit of the downward forcing of the roll 36 may be substituted for that just described, as for instance a yoke and screw arrangement such as that hereinafter described with reference to the limiting of the downward movement of the upper web-forming roll.

A hydraulic cylinder 53 is provided on the frame 43 adjacent the cylinder 50 and a pull-back plunger 54 operates within this cylinder. 75

The plunger 54 is connected at its upper end with a yoke 55 and links 56 connect the yoke with the bearing 48, one link extending at each side of the cylinder 53. Liquid under pressure is constantly supplied to the cylinder 53 so that when the liquid is exhausted from the cylinder 53 the roll 35 will be raised from the bloom. The power of the cylinder 50 is of course substantially greater than the power of the cylinder 53 so that the former will readily overcome the latter when liquid under pressure is supplied to the cylinder 50. By this arrangement the operation of the edging rolls may be controlled at will to thereby aid in the attainment of the desired shape of the bloom.

Two guide rolls 57 are provided one at each side of the rolls 35 and 36. Each roll 57 is similarly carried in the following manner (see particularly Figs. 7 and 8). It is pivotally mounted in a jaw 58a formed in one arm 58b of a bell crank lever 58. The lever 58 is in turn pivotally connected to a bracket 59 which is cast integrally with the frame 43 and comprises upper and lower spaced plates 59a which extend to the right from the frame and are joined at their outer edges by a web 59b. The lever is disposed between these plates and a pin 58c is passed through the plates and lever to provide the pivotal connection therebetween. An adjusting screw 59c is passed through a threaded opening provided therefor in the web and bears at its inner end against the other arm 58d of the bell crank lever. A lock nut 59d is provided for the screw 59c. A wedge 59e is passed through oppositely disposed slots provided therefor in the plates 59a and backs up against a solid part 43a of the frame which extends between the plates 59a. The outer face of the wedge is curved and fits into a groove 58e formed in the arm 58d. A suitable washer (not shown) may be provided on the inner end of the screw 59c, which washer would preferably be flat on its face bearing against the arm 58d and cupped on its opposite face to fit around the end of the screw.

It will be obvious that by adjustment of the wedges and screws the bell crank levers and rolls 57 may be adjusted to various positions so as to better accommodate different sizes of blooms. The wedge slots will of course be sufficiently large to provide the necessary clearance for movement of the wedges during adjustment. By adjustment of the position of the frame 43 the operation of the guide rolls 57 may be controlled to thereby aid in the attainment of the desired shape of the bloom.

While the aforescribed parts provide a practical means for manually adjusting the positions of the guide rolls 57, it will be understood that any of the various other arrangements for adjusting the guide rolls, which arrangements are well known in the art, may be substituted therefor permitting the rolls to be adjusted either manually or automatically with movements of the frame 43 in which latter case of course the rolls will be moved toward each other along diverging lines simultaneously with the movement of the frame 43 toward the main roll 2.

In the operation of the apparatus the rolls 57 bear against the exterior surface of the bloom opposite the respective rolls 20 and at the sides of the rolls 35 and 36 and are moved away from or toward the roll 2 in unison when the frame 43 is correspondingly moved. The principal purpose of the guide rolls is to assist in holding the bloom in its proper position.

Coming now to the particular parts of the mill embodying the novel features of the present invention, that is to say the improved interior circumferential web-forming mechanism shown in detail in Figs. 3 to 6, the desired contour of the web is produced by a lower roll 60 and an upper roll 61 carried, as will be presently described, by the carriage 12.

An arbor 62 is integrally formed on the roll 60 and extends upwardly therefrom axially 10 thereof into a socket 63 which is formed in the roll 61. A shank 64 is also integrally formed on the roll 60 and extends downwardly therefrom axially thereof. Both of the rolls 60 and 61 are vertically adjustable as will presently appear. 15

A vertical rotary shaft 65 is mounted in upper, middle and lower bearings 67, 68 and 69 respectively which are formed in the lower frame unit, indicated generally by the numeral 66, of the carriage 12. A suitable bushing is provided 20 in each of these three bearings. The upper end of the shaft 65 is enlarged and formed as a sleeve 70 into which the shank 64 extends. Vertical slots are formed in the sleeve 70 and the shank 64 and a driving key 71 is provided in these slots 25 so that the roll 60 will rotate with the shaft 65. In certain cases where it is not desirable to supply rotating power to the roll 60, the action of the bloom being rolled will rotate the roll 60 and the shaft 65 will be rotated by virtue 30 of the driving key thus securing proper journal action in the three bearings of the shaft. In this case the motor connections with the shaft 65 would of course be eliminated.

A cylindrical thrust block 72 is provided in 35 the lower bearing 69 beneath the lower end of the shaft 65, the bushing in this bearing surrounding both the lower end of the shaft 65 and the block 72. A suitable thrust washer 73 is disposed between the adjacent ends of the block 40 and shaft. The lower end of the thrust block 72 rests on the horizontal upper surface of a wedge block 76. The wedge block 76 is of rectangular shape in its horizontal cross section and is adapted to slide vertically in a correspondingly 45 shaped cavity 74 provided in the lower frame unit 66 as hereinafter further mentioned. The lower surface of the block 76 is slanted and engages a slanting upper surface of a wedge 77 which is disposed below the block 76. The wedge 77 is adapted to slide horizontally on a part of the lower frame unit 66 in a suitable cavity 77a provided in this unit as hereinafter further mentioned. Since the distance from front to back (as viewed in Fig. 3) of the wedge block 76 is the 55 same as the distance from front to back of the wedge 77 and of their corresponding working cavities 74 and 77a, and as this distance is not as great as the diameter of the thrust block 72, counter-bored recesses indicated at 75 and 75a 60 are formed in the front and back faces of the cavity 74 extending downwardly from the top thereof. These recesses are bored to a diameter equal to the diameter of the thrust block 72 and to a depth sufficient to permit the thrust block 72 65 and consequently the shaft 65 to be lowered axially the full amount of the pitch of the slanting upper surface of the wedge 77 as the wedge is withdrawn to the right.

The wedge 77 is secured at one end to a stem 70 78 which stem is in turn secured to a piston 79 which operates in a hydraulic cylinder 80 carried on the frame unit 66 in a cavity 80a provided therein for the cylinder as hereinafter further mentioned. The opposite end of the wedge 77 is 75

secured to a piston 81 which operates in a hydraulic cylinder 82 also carried on the frame unit 66 in a suitable cavity 82a provided therein as hereinafter further mentioned. Movement of 5 the wedge 77 by action of the piston 79 to the left as viewed in Fig. 3 obviously will effect a raising of the blocks 76 and 72, shaft 65 and roll 60. These parts will drop by gravity as the wedge is withdrawn, that is to say moved to the right as 10 viewed in Fig. 3, by the piston 81. The cylinder 82 will be constantly supplied with liquid under pressure so that whenever pressure is released in the cylinder 80 the wedge 77 will be forced to the right by the piston 81. The cylinder 80 is of 15 course adapted to provide substantially greater power than the cylinder 82 so that the former will always overcome the latter when liquid under pressure is supplied to the cylinder 80.

The bottom portion of the lower frame unit 66 is made in two parts 66a which are bolted together by transverse bolts 66b and through which the lower bolts 13 extend. The parts 66a are bolted to the upper portions of the unit 66 by vertical bolts 66c. The opposite faces of the parts 25 66a are shaped to provide the cavities 80a, 82a, 71a and 74 for the cylinders 80 and 82, the wedge 77, the wedge block 76 and the recesses 75 and 75a for the thrust block 12. The cavity 71a in which both the wedge 77 and the stem 78 move, and which is at the left end, as viewed in 30 Fig. 3, of the cavity 80a, is rectangular and only of sufficient height and width to accommodate the wedge 77 and stem 78. This width is less than the width of the piston 79. Thus the piston 35 79 is limited in its outward movement by the edges of the side walls of the cavity 71a and consequently the upward movement of the roll 60 is thereby limited.

40 Thrust washers of various thicknesses may be substituted for the thrust washer 73 above mentioned in order to vary the initial and final vertical positions of the roll 60 so as to roll webs of various thicknesses and in various positions on the blooms.

45 Other means for vertically adjusting the shaft 65 may of course be provided in place of those aforescribed, such as for instance a vertically disposed cylinder and piston mounted below the shaft or a suitably geared screw feed with an electric motor drive.

50 A bevel gear 83 is mounted by a spline connection on the shaft 65 between the bearings 68 and 69, a vertical slot 65a being provided in the shaft, and a key 83a which slidably fits into the slot 55 being carried by the bevel gear 83. Positive rotation of the shaft by the bevel gear is thus insured while the shaft is permitted vertical movement relative to the bevel gear. The lower frame unit 66 is suitably shaped to accommodate this gear. 60 By virtue of the spline connection the shaft 65 may be readily raised when it is desired to change the washer 73 for the purpose hereinbefore-mentioned. A suitable slot (not shown) for the removal laterally of the washer 73, or its replacement, is made through one side of the bushing and its surrounding bearing 69. This arrangement avoids the necessity of the complete removal of the shaft 65 when changing washers. A 65 suitable filled block, preferably of bronze, will be provided for closing this slot. A bevel gear 84 is in mesh with the gear 83 and is mounted on the right end of a shaft 85 which shaft is rotatably mounted at this end in a suitable bearing 86 carried on the lower frame unit 66 of the carriage 70 75 12. The shaft 85 extends longitudinally of the

mill as shown in Fig. 1 and its left end extends into a sleeve 87 with which sleeve the shaft is in spline engagement as indicated at 88. The sleeve 87 is rotatably mounted in a bearing 89 carried on the frame 5 and a gear 90 is mounted on the 5 right end of this sleeve. The gear 90 is in mesh with the gear 42 hereinbefore mentioned. It will thus be seen that the roll 60 may be positively rotated by power from the shaft 11. The spline engagement of the shaft 85 with the sleeve 87 10 permits the shaft 85 to move longitudinally with the carriage 12 relative to the sleeve while insuring its positive rotation with the sleeve.

A shank 91 is integrally formed on the roll 61 and extends upwardly therefrom axially thereof 15 into a bushing 92 which is disposed within a sleeve extension 93 integrally formed on the lower end of a plunger 94. The plunger 94 operates within a cylinder 95 which is formed as an integral part of the upper frame unit, indicated generally by 20 the numeral 96, of the carriage 12. Suitable thrust washers 97 are provided around the shank 91 between the lower end of the extension 93 and the upper surface of the roll 61. Downward vertical movement of the roll 61 is obtained by 25 the introduction of fluid under pressure into the cylinder 95 which forces the plunger 94 downward. A cylinder head 98 is provided for the upper end of the cylinder 95 and is suitably secured thereto by studs 98a. A bushing is provided in 30 the cylinder 95 around the plunger 94.

Two cylinders 99 are also formed integrally with the frame unit 96, one cylinder 99 on each of the opposite sides of the cylinder 95. A lifting or pull-back plunger 100 is disposed in each 35 of the cylinders 99. A horizontal yoke 101 is disposed above the cylinders 95 and 99 and each of the plungers 100 is secured at its upper end portion to the yoke, the portion being of a reduced diameter and extending through an opening formed therefor in the yoke and a nut 102 being provided at the upper end of the portion. Two openings 103 are formed in the cylinder head 98, and piston rods 104 are passed one through 40 each of the openings 103 and are screwed into 45 the plunger 94. The upper end portion of each of the rods 104 is of a reduced diameter and extends through an opening formed therefor in the yoke 101, a nut 105 being provided on the upper end of each rod. The upper end portions of the 50 plungers 100 and the rods 104 being of reduced diameters provide shoulders against which the yoke 101 bears when the nuts 102 and 105 are drawn up.

55 In order to limit the downward movement of the roll 61, lugs 96a are formed on the frame unit 96 one at the side of each cylinder 99 and bosses 101a are formed on the opposite ends of the yoke 101 immediately above the lugs. A threaded vertical opening is formed in each boss and an adjusting screw 101b, provided with a lock nut 101c, is screwed through each opening. It will be apparent that the lower ends of the screws 101b will strike against the lugs 96a so as to limit the downward movement of the yoke 101 and consequently the roll 61 and that the lowermost position for the roll 61 may be varied by adjusting the screws 101b.

60 Suitable packing rings are provided at the lower ends of the plungers 100, around the rods 70 104 at the upper ends of the openings 103 and at the upper end of the plunger 94, each of these packing rings being secured in place in the usual manner.

65 A circumferential groove 106 is formed in the 75

shank 91 and holes 107 are formed in the bushing 92 and extension 93. A retaining plug 108 is passed through the holes 107 into the groove 106 and serves to retain the roll 61 in engagement with the plunger 94 when the plunger is moved to open position as hereinafter described. This arrangement also permits of easy changing of the roll 61.

Fluid under pressure will be constantly supplied to the cylinders 99 so that when pressure is exhausted from the cylinder 95 the plunger 94 and hence the roll 61 will be raised. The cylinder 95 of course provides substantially greater power than the cylinders 99 so that the plunger 94 will be readily forced downwardly overcoming the power of the cylinders 99 when fluid under pressure is supplied to the cylinder 95.

The rolling action of the roll 61 is obtained entirely by contact drive from the bloom being rolled and by friction contact with the arbor 62. It will be apparent that by suitable control of the operation of the various control mechanisms aforescribed for the rolls 60 and 61 a control thereof may be effected so as to aid in the attainment of the desired shape of the bloom.

In Fig. 9 however there is illustrated a modified construction of rolls whereby an upper roll 109 is power driven with the lower roll 110 which rolls correspond to the rolls 61 and 60 respectively. The modified construction is the same as the first described construction excepting that the arbor 111 of the roll 110 is of increased length and the socket 112 of the roll 109 is also of increased depth to accommodate the arbor 111. Vertical keyways are formed in the arbor 111 and the wall of the socket 112 and a key is provided in these keyways as indicated at 113. The key is fastened to the keyway in the socket and to insure free entering of the lower end of the key into the upper end of the keyway in the arbor when the rolls are being closed together the lower end of the key is tapered and the upper end of the keyway in the arbor is flared. The lower end of the keyway in the arbor will of course be of such height above the face of the roll 110 that when the rolls 109 and 110 are separated the maximum amount, at the beginning of a rolling operation, no part of this keyway in the arbor will be exposed below the bottom face of the roll 109 so that no metal of the bloom being rolled can be pressed into this keyway.

In Fig. 10 there is illustrated another modified construction of rolls wherein an upper roll 114 is driven by power and a lower roll 115 is idle getting its rotating motion from contact by the bloom being rolled and a shank 116. Here the lower roll 115 has no shank or arbor but a central opening 117 is formed therein. The shank 116 extends through the opening 117 and permits free rotation of the roll 115 thereon. The upper end portion of the shank 116 extends into a socket 118 formed in the upper roll 114 and is keyed to this roll in the same manner as described with reference to the construction shown in Fig. 9, a similarly formed key and keyways being provided. The lower end portion 116a of the shank 116 is enlarged and fits within and is keyed to the sleeve 78 of the enlarged upper end of the shaft 65.

Horizontal aligned bearings are formed at one side of the carriage, one bearing in the upper part of the frame unit 66 and two bearings in the lower part of the frame unit 66, the latter two being disposed one at each side of the bearing of the unit 66 (only the bearing of the unit 66 being shown as indicated at 119). A bolt 120 is passed

through these bearings, a hinge connection being thus provided between these two frame units whereby the upper frame unit and parts carried thereby may be swung upwardly away from the lower frame unit separating the rolls 60 and 61 and permitting the insertion or removal of blooms or rings to or from operating position.

Two toothed sectors 121 are rigidly secured to the frame unit 66, one at each of the opposite sides of the hinge bearing. A bracket 122 is bolted to the lower frame unit 66 and a vertical double-acting air cylinder 123 is bolted to the bracket 122. A piston 124 is disposed within the cylinder 123. The lower head 125 of the cylinder 123 is preferably formed as an integral part thereof and the upper head 126 is formed as a separate part and is suitably secured to the cylinder by studs 127. An opening 128 is formed centrally in the head 126 and a piston rod 129 extends therethrough and is suitably secured at its lower end to the piston 124. Packing rings are provided for the piston 124 and around the rod 129 at the opening 128 as in usual practice, as clearly shown in Fig. 3. Two spaced, vertical, toothed racks 130, one in mesh with each of the sectors 121, are secured to a crosshead 131 which crosshead is in turn secured to the upper end of the rod 129. Brackets 132 are secured to the lower frame unit 66 and a guide bar 133 is secured to the ends of the brackets for guiding the respective racks 130 and holding them in proper alignment and in mesh with their respective sectors 121.

It will be apparent that downward movement of the piston 124 will effect the upward or opening swinging movement of the upper frame unit 66 and upward movement of the piston will effect downward or closing swinging movement of this unit. As the combined assembly of the upper frame unit and parts carried thereby including the cylinder 95 and plunger 94 are of considerable weight and will be swung through an angle of 90 degrees, practically as much power will be required to start the assembly back from open position toward the closed position as is required for the beginning of the opening movement. The cylinder 123 is for this reason made double-acting and suitable valves of any well-known design are provided for controlling the admission and exhaust of air under pressure into and from the opposite ends of this cylinder so as to move the frame unit 66 and its associated parts both from closed to open position and from open to closed position. Proper cushioning of the opening and closing movements of the upper frame unit and the parts carried thereby is provided by suitable valve means of any well-known design in the air pressure control pipes leading to the top and bottom ends of the cylinder 123.

At the side of the carriage opposite the hinge connection means are provided for locking the upper frame unit 66 in closed position to the lower frame unit 66, the locking effect of which means is adapted for quick release. The lower end of the upper frame unit 66 at this side of the carriage is formed with an outwardly extending flange 134 having a slanting upper surface, and a corresponding outwardly extending flange 135 having a slanting lower surface is formed on the upper part of the lower frame unit 66. The adjacent surfaces of the flanges 134 and 135 are horizontal and adapted for even engagement. The flange 135 is spaced downwardly from the top of the frame unit 66 providing a slanting substantially vertical surface 136 and the frame unit 75

96 is provided with a corresponding slanting surface 137 at the inner end of the flange 134, the surfaces 136 and 137 being adapted for engagement when the frame unit 96 is moved to closed position.

5 A horizontal, upwardly extending, converging tongue is integrally formed on the flange 135 and a complimentary groove is formed in the flange 134, as indicated at 138. When the upper frame 10 unit is in closed position this tongue extends into this groove, further insuring alignment and proper positioning of the two frame units.

15 A U-shaped clamp 139 is shaped to fit over the upper slanting surface of the flange 134 and the lower slanting surface of the flange 135. These surfaces converge in an outward direction from the carriage and the surfaces of the clamp which engage them also converge in the same direction. A stem 140 is formed on the clamp 139 and extends outwardly therefrom and is secured to a piston 141. The piston 141 is adapted to be reciprocated by air under pressure in a cylinder 142 which is bolted to a bracket 143 which bracket is in turn secured by studs 144 to the lower frame 20 unit 66. The cylinder 142 is double-acting and outward movement of the piston 141 (to the left as shown in Fig. 3) effects movement of the clamp 139 away from the flanges 134 and 135 unlocking the upper frame unit from the lower frame 25 unit, while inward movement of the piston when the upper frame unit is in closed position effects the engagement of the clamp with the flanges, the two frame units being thereby locked together as shown in Fig. 3.

30 It will be apparent that when the clamp is in locked position, by virtue of the fluid pressure at the left side of the piston 141, the two flanges 134 and 135 are forced tightly together, with the tongue on the flange 135 in its groove in the flange 134 and with the surface 136 forced tightly 35 against the surface 137. The opposite side of the unit 96 is held as aforescribed to the unit 66 by the aligned bearings and the bolt 120. The two units 66 and 96 are thus secured together 40 as a substantially unitary structure and when horizontal adjustment is effected, through the rods 13, the entire carriage 12 will move as a single unit and horizontal pressure will be transmitted to the upper roll as well as the lower roll. In other words the upper roll will receive its horizontal 45 rolling pressure from the upper frame unit 96 as well as from the lower frame unit 66 through the arbor 62.

50 The pressure fluid connections from the supply pipes to the various cylinders of the mill are constructed as in usual practice by telescopic or swinging joints and there will be control valves of any well-known or preferred design (not shown) whereby the fluid supply for the various 55 cylinders may be controlled.

55 A ring will be rolled in the mill from a bloom at the proper temperature substantially in the usual well-known manner which is unnecessary to set forth herein. The present invention provides a construction which is simple and efficient in its operation and permits easy and speedy adjustment from engaged to disengaged position and vice versa of the web-forming rolls so that the removal of a rolled ring from, and the insertion 60 of a fresh bloom into operating position in the mill can be accomplished with a minimum expenditure of time and effort. In effect a composite device is provided by this invention for forming the interior web on the bloom, which 65 device provides an annular groove for the web

and embodies two relatively movable parts, each of which parts provides a wall of the groove which has surface contact with the bloom metal that forms the web and a wall which has rolling contact with the bloom. A third part of the device 70 provides a bottom wall for the groove which has rolling contact with the bloom metal that forms the web.

75 While the adjustable groove mechanism of the present invention has been described in connection with a particular type of mill it will be understood that it is not so limited in its application but in its broader aspect the invention may be employed with other suitable types of mills, such for instance as that shown in United States Patent 664,799 issued to F. A. Wheeler, December 25, 1900 wherein the main roller moves toward the pressure roller. Further it will be understood that many and various changes and modifications in form, arrangement of parts and details of construction of the mechanism hereinbefore described may be made without departing from the spirit of the invention and that all such changes and modifications as fall within the scope of the appended claims are contemplated as a 80 part of this invention.

85 The invention claimed and desired to be secured by Letters Patent is:

1. A rolling mill for rolling a metal annular bloom comprising a frame having two spaced 90 parts and a third part connecting said two spaced parts providing an open space between the three said parts; a composite rolling device providing a groove when in operative rolling position, said device being disposed across said space and connected to said two spaced parts and having two axially spaced rolls, the adjacent end faces of said rolls normally forming walls of said groove, said rolls being adapted for rolling the inner surface of said bloom, one of said rolls being carried 95 by one of said two spaced parts and the other of said rolls being carried by the other of said two spaced parts; means for supporting said bloom with said inner surface adjacent said groove and rolls, said rolls being adapted for axial adjustment 100 to vary the width of said groove whereby, during the operation of said mill, an annular web of predetermined width can be formed on said inner surface of said bloom; and means for relatively moving said rolls from operative rolling position 105 to sufficiently spaced relation to provide a clear, free space between said adjacent end faces thereof to permit the passage through said free space of a bloom both to and from operative position.

110 2. A rolling mill for rolling a metal annular bloom, comprising a frame having two spaced parts and a third part connecting said two spaced parts providing an open space between the three said parts; a composite rolling device providing a groove when in operative rolling position, said device being disposed across said space and connected to said two spaced parts, and having two axially spaced rolls, the adjacent end faces of said rolls normally forming walls of said groove, said rolls being adapted for rolling the inner surface 115 of said bloom, one of said rolls being carried by one of said two spaced parts and the other of said rolls being carried by the other of said two spaced parts; means for supporting said bloom with said inner surface adjacent said groove and rolls, said rolls being adapted for axial adjustment to vary the width of said groove; means for moving said rolls to adjust the position of said groove axially of said bloom whereby, during the operation of said mill, an annular web of pre- 120

determined width and position can be formed on said inner surface of said bloom; and means for relatively moving said rolls from operative rolling position to sufficiently spaced relation to provide 5 a clear, free space between said adjacent end faces thereof to permit the passage through said free space of a bloom both to and from operative position.

3. A rolling mill for rolling a metal annular bloom, comprising a frame having two spaced parts and a third part connecting said two spaced parts providing an open space between the three said parts; a composite rolling device providing a groove when in operative rolling position, said device being disposed across said space and connected to said two spaced parts, and having two axially spaced rolls, the adjacent end faces of said rolls normally forming walls of said groove, said rolls being adapted for rolling the inner surface 10 of said bloom, one of said rolls being carried by one of said two spaced parts and the other of said rolls being carried by the other of said two spaced parts; means for supporting said bloom with said inner surface adjacent said groove and rolls 15 whereby, during the operation of said mill, an annular web can be formed on said inner surface of said bloom; and means for relatively moving said rolls from operative rolling position to sufficiently spaced relation to provide a clear, free 20 space between said adjacent end faces thereof to permit the passage through said free space of a bloom both to and from operative position.

4. A rolling mill for rolling a metal annular bloom, comprising a frame having two spaced parts and a third part connecting said two spaced parts providing an open space between the three said parts; a composite rolling device providing a groove when in operative rolling position, said device being disposed across said space and connected to said two spaced parts, and having two axially spaced rolls and an arbor extending throughout the space between said rolls, the adjacent end faces of said rolls and the face of said arbor therebetween normally forming the 25 walls of said groove, said rolls being adapted for rolling the inner surface of said bloom, one of said rolls and said arbor being carried by one of said two spaced parts and the other of said rolls being carried by the other of said two spaced parts; and means for supporting said bloom with said inner surface adjacent said groove and rolls 30 whereby, during the operation of said mill, an annular web can be formed on the inner surface of said bloom; and means for relatively moving one of said rolls with said arbor and the other of said rolls from operative rolling position to sufficiently spaced relation to provide a clear, free 35 space between said roll and arbor and said other roll to permit the passage through said free space 40 of a bloom both to and from operative position.

5. A rolling mill for rolling a metal annular bloom, comprising a frame having two spaced parts and a third part connecting said two spaced parts providing an open space between the three said parts; a composite device providing a groove when in operative position having a wall thereof formed on one part of said device and an opposite wall thereof formed on another part of said device, the two said device parts being adapted 45 for relative movement to thereby vary the width of said groove, said device being disposed across said space and connected to said two spaced frame parts, one of said device parts being carried by one of said frame parts and the other of said device parts being carried by the other 50 of said frame parts; controllable means for effecting said relative movement; means for supporting said bloom for continuous engagement with said device, with said groove adjacent the inner surface of said bloom; means adapted for effecting relative movement of said bloom and device to effect continuous and progressive engagement of said device around said inner surface of said bloom whereby, by control of said relative movement of said two device parts, material of said bloom can be shaped within said groove to form an inner annular web of predetermined width on said inner surface of said bloom; and means for relatively moving said device parts from operative position to sufficiently spaced relation to provide a clear, free space 55 between said walls thereof to permit the passage through said free space of a bloom both to and from operative position.

6. A rolling mill for rolling a metal annular bloom, comprising a frame having two spaced parts and a third part connecting said two spaced parts providing an open space between the three said parts; a composite device providing a groove when in operative position having a wall thereof formed on one part of said device and an opposite wall thereof formed on another part of said device, the two said device parts being adapted for relative movement to thereby vary the width of said groove, said device being disposed across said space and connected to said two spaced frame parts, one of said device parts being carried by one of said frame parts and the other of said device parts being carried by the other of said frame parts; controllable means for effecting said relative movement; means for supporting said bloom for continuous engagement with said device, with said groove adjacent the inner surface of said bloom; means for adjusting the relative positions of said device and bloom to vary the distance between said device and the adjacent outer surface of said bloom; means adapted for effecting relative movement of said bloom and device to effect continuous and progressive engagement of said device around said inner surface of said bloom whereby, by control of said relative movement of said two device parts, material of said bloom can be shaped within said groove to form an inner annular web of predetermined width on said inner surface of said bloom; and means for relatively moving said device parts from operative position to sufficiently spaced relation to provide a clear, free space between said walls thereof to permit the passage through said free space of a bloom both to and from operative position.

7. A rolling mill for rolling a metal annular bloom, comprising a frame having two spaced parts and a third part connecting said two spaced parts providing an open space between the three said parts; a main roll adapted for operation upon the outer surface of said bloom; a composite rolling device providing a groove when in operative rolling position, said device being disposed across said space and connected to said two spaced parts, and having two rolls, each of said two rolls having a surface, the two said surfaces being oppositely disposed in spaced relation to each other normally forming walls of said groove, and a rolling surface facing said main roll, said device being thereby adapted for continuous rolling engagement with the inner surface of said bloom, with said groove adjacent thereto, one of said two rolls being carried by one of said two spaced parts and the other of said two spaced parts being carried by the other of said two spaced parts; controllable means for effecting said relative movement; means for supporting said bloom for continuous engagement with said device, with said groove adjacent the inner surface of said bloom; means adapted for effecting relative movement of said bloom and device to effect continuous and progressive engagement of said device around said inner surface of said bloom whereby, by control of said relative movement of said two device parts, material of said bloom can be shaped within said groove to form an inner annular web of predetermined width on said inner surface of said bloom; and means for relatively moving said device parts from operative position to sufficiently spaced relation to provide a clear, free space between said walls thereof to permit the passage through said free space of a bloom both to and from operative position.

8. A rolling mill for rolling a metal annular bloom, comprising a frame having two spaced parts and a third part connecting said two spaced parts providing an open space between the three said parts; a main roll adapted for operation upon the outer surface of said bloom; a composite rolling device providing a groove when in operative rolling position, said device being disposed across said space and connected to said two spaced frame parts, one of said device parts being carried by one of said frame parts and the other of said device parts being carried by the other of said frame parts; controllable means for effecting said relative movement; means for supporting said bloom for continuous engagement with said device, with said groove adjacent the inner surface of said bloom; means adapted for effecting relative movement of said bloom and device to effect continuous and progressive engagement of said device around said inner surface of said bloom whereby, by control of said relative movement of said two device parts, material of said bloom can be shaped within said groove to form an inner annular web of predetermined width on said inner surface of said bloom; and means for relatively moving said device parts from operative position to sufficiently spaced relation to provide a clear, free space between said walls thereof to permit the passage through said free space of a bloom both to and from operative position.

- rolls being carried by the other of said two spaced parts; means for effecting relative movement of said rolling surfaces and said main roll to thereby vary the distance between said rolling surfaces and said main roll; means cooperating to support said bloom with its outer surface adjacent said main roll and its inner surface adjacent said two rolls and said groove; controllable means for effecting relative movement of the two said spaced surfaces to thereby vary the width of said groove whereby, by control of said relative movement of the two said spaced surfaces, material of said bloom can be shaped within said groove to form an annular web of predetermined width on said inner surface of said bloom; and means for relatively moving said two rolls from operative rolling position to sufficiently spaced relation to provide a clear, free space between said surfaces to permit the passage through said free space of a bloom both to and from operative position.
8. A rolling mill for rolling a metal annular bloom, comprising a frame having two spaced parts and a third part connecting said two spaced parts providing an open space between the three said parts; a main roll adapted for operation upon the outer surface of said bloom; a composite rolling device providing a groove when in operative rolling position, said device having two axially spaced rolls, the adjacent end faces of said two rolls normally providing walls of said groove, each of said two rolls having a rolling surface facing said main roll, said device being thereby adapted for continuous rolling engagement with the inner surface of said bloom, with said groove adjacent thereto, one of said two rolls being carried by one of said two spaced parts and the other of said two rolls being carried by the other of said two spaced parts; means for effecting relative movement of said device and said main roll to thereby vary the distance between said rolling surfaces and said main roll; means cooperating to support said bloom with its outer surface adjacent said main roll and its inner surface adjacent said two rolls and said groove; separate controllable means for each of said two rolls for effecting movement thereof relative to the other of said two rolls to thereby vary the width of said groove whereby, by control of said relative movements of said two rolls, material of said bloom can be shaped within said groove to form an annular web of predetermined width on said inner surface of said bloom; and means for relatively moving said two rolls from operative rolling position to sufficiently spaced relation to provide a clear, free space between said adjacent end faces to permit the passage through said free space of a bloom both to and from operative position.
9. A rolling mill for rolling a metal annular bloom, comprising a frame having two spaced parts and a third part connecting said two spaced parts providing an open space between the three said parts; a main roll adapted for operation upon the outer surface of said bloom; a composite rolling device providing a groove when in operative rolling position, said device having two axially spaced rolls, one of said two rolls having a socket centrally formed therein and the other of said two rolls having an arbor projecting axially from the central portion thereof and extending throughout the space between said two rolls and into said socket, the adjacent end faces of said two rolls and the face of said arbor therebetween normally forming the walls of said groove, each of said two rolls having a rolling surface facing said main roll, said device being thereby adapted for continuous rolling engagement with the inner surface of said bloom, with said groove adjacent thereto, and means within said socket keying said arbor to said socketed roll; means for effecting relative movement of said device and said main roll to thereby vary the distance between said rolling surfaces and said main roll; means cooperating to support said bloom with its outer surface adjacent said main roll and its inner surface adjacent said two rolls and said groove; and controllable means for effecting relative movement of said two rolls to thereby vary the width of said groove whereby, by control of said relative movement of said two rolls, material of said bloom can be shaped within said groove to form an annular web of predetermined width on said inner surface of said bloom.
10. A rolling mill for rolling a metal annular bloom, comprising a main roll adapted for operation on the outer surface of said bloom; a composite device providing a groove, said device having two axially spaced rolls, one of said two rolls having a socket centrally formed therein and the other of said two rolls having an arbor projecting axially from the central portion thereof and extending throughout the space between said two rolls and into said socket, the adjacent end faces of said two rolls and the face of said arbor therebetween forming the walls of said groove, each of said two rolls having a rolling surface facing said main roll, said device being thereby adapted for continuous rolling engagement with the inner surface of said bloom, with said groove adjacent thereto, and means within said socket keying said arbor to said socketed roll; means for effecting relative movement of said device and said main roll to thereby vary the distance between said rolling surfaces and said main roll; means cooperating to support said bloom with its outer surface adjacent said main roll and its inner surface adjacent said two rolls and said groove; and controllable means for effecting relative movement of said two rolls to thereby vary the width of said groove whereby, by control of said relative movement of said two rolls, material of said bloom can be shaped within said groove to form an annular web of predetermined width on said inner surface of said bloom; and means for relatively moving said socketed roll and the other of said two rolls and its projecting arbor from operative rolling position to sufficiently spaced relation to provide a clear, free space between said socketed roll and the other of said two rolls and its projecting arbor to permit the passage through said free space of a bloom both to and from operative position.
11. A rolling mill for rolling a metal annular bloom, comprising a main roll adapted for operation upon the outer surface of said bloom; a composite device providing a groove, said device having two axially spaced rolls, one of said two rolls having a socket centrally formed therein and the other of said two rolls having an axial opening formed centrally therethrough, an arbor extending through said opening, throughout the space between said two rolls and into said socket, the adjacent end faces of said two rolls and the face of said arbor therebetween forming the walls of said groove, each of said two rolls having a rolling surface facing said main roll, said device being thereby adapted for continuous rolling engagement with the inner surface of said bloom, with said groove adjacent thereto, and means within said socket keying said arbor to said socketed roll; means for effecting relative movement of said device and said main roll to thereby vary the distance between said rolling surfaces and said main roll; means cooperating to support said bloom with its outer surface adjacent said main roll and its inner surface adjacent said two rolls and said groove; and controllable means for effecting relative movement of said two rolls to thereby vary the width of said groove whereby, by control of said relative movement of said two rolls, material of said bloom can be shaped within said groove to form an annular web of predetermined width on said inner surface of said bloom.

rolling surface facing said main roll, said device being thereby adapted for continuous rolling engagement with the inner surface of said bloom, with said groove adjacent thereto, and means within said socket keying said arbor to said socketed roll; means for effecting relative movement of said device and said main roll to thereby vary the distance between said rolling surfaces and said main roll; means cooperating to support said bloom with its outer surface adjacent said main roll and its inner surface adjacent said two rolls and said groove; and controllable means for effecting relative movement of said two rolls to thereby vary the width of said groove whereby, by control of said relative movement of said two rolls, material of said bloom can be shaped within said groove to form an annular web of predetermined width on said inner surface of said bloom.

12. A rolling mill for rolling a metal annular bloom, comprising a main roll adapted for operation upon the outer surface of said bloom; a carriage adjacent said main roll including a frame having two spaced parts and a third part connecting said two spaced parts providing an open space between the three said parts; a composite rolling device carried by said carriage providing a groove when in operative rolling position, said device being disposed across said space and connected to said two spaced parts, and having two axially spaced rolls, the adjacent end faces of said two rolls providing walls of said groove, each of said two rolls having a rolling surface facing said main roll, said device being thereby adapted for continuous rolling engagement with the inner surface of said bloom, with said groove adjacent thereto, one of said two rolls being carried by one of said two spaced parts and the other of said two rolls being carried by the other of said two spaced parts; means for effecting relative movement of said carriage and said main roll to thereby vary the distance between said rolling surfaces and said main roll; means cooperating to support said bloom with its outer surface adjacent said main roll and its inner surface adjacent said two rolls and said groove; controllable means carried by said carriage for effecting relative movement of said two rolls to thereby vary the width of said groove whereby, by control of said relative movement of said two rolls, material of said bloom can be shaped within said groove to form an annular web of predetermined width on said inner surface of said bloom; and means for relatively moving said two rolls from operative rolling position to sufficiently spaced relation to provide a clear, free space between said adjacent end faces thereof to permit the passage through said free space of a bloom both to and from operative position.

13. A rolling mill for rolling a metal annular bloom, comprising a main roll adapted for operation upon the outer surface of said bloom; a carriage adjacent said main roll comprising two frame units, one unit being hingedly connected with the other unit for swinging movements to open and closed positions relative to said other unit; a composite device providing a groove, said device having two rolls, said two rolls, when in operative position, being axially spaced with their adjacent end faces providing walls of said groove, each of said two rolls having a rolling surface facing said main roll when said two rolls are in operative position, said device being thereby adapted for continuous rolling engagement with the inner surface of said bloom, with said groove

adjacent thereto, one of said two rolls being carried by one of said frame units and the other of said two rolls being carried by the other of said frame units whereby when said swinging unit is in open position blooms may be inserted and removed, and when said swinging unit is in closed position said two rolls will be in operative position; means for effecting relative movement of said carriage and said main roll to thereby vary the distance between said rolling surfaces and said main roll; means cooperating to support said bloom with its outer surface adjacent said main roll and its inner surface adjacent said two rolls and said groove; and controllable means carried by said carriage for effecting relative movement of said two rolls to thereby vary the width of said groove whereby, by control of said relative movement of said two rolls, material of said bloom can be shaped within said groove to form an annular web of predetermined width on said inner surface of said bloom.

14. A rolling mill for rolling a metal annular bloom, comprising a main roll adapted for operation upon the outer surface of said bloom; a carriage adjacent said main roll comprising two frame units, one unit being hingedly connected with the other unit for swinging movements to open and closed positions relative to said other unit; a composite device providing a groove, said device having two rolls, said two rolls, when in operative position, being axially spaced with their adjacent end faces providing walls of said groove, each of said two rolls having a rolling surface facing said main roll when said two rolls are in operative position, said device being thereby adapted for continuous rolling engagement with the inner surface of said bloom, with said groove adjacent thereto, one of said two rolls being carried by one of said frame units and the other of said two rolls being carried by the other of said frame units whereby, when said swinging unit is in open position, blooms may be inserted and removed, and when said swinging unit is in closed position said two rolls will be in operative position; means for effecting relative movement of said carriage and said main roll to thereby vary the distance between said rolling surfaces and said main roll; means cooperating to support said bloom with its outer surface adjacent said main roll and its inner surface adjacent said two rolls and said groove; controllable means carried by said carriage for effecting relative movement of said two rolls to thereby vary the width of said groove whereby, by control of said relative movement of said two rolls, material of said bloom can be shaped within said groove to form an annular web of predetermined width on said inner surface of said bloom; and power means operably connected with said swinging frame unit to effect said opening and closing movements.

15. A rolling mill for rolling a metal annular bloom, comprising a main roll adapted for operation upon the outer surface of said bloom; a carriage adjacent said main roll comprising two frame units, one unit being hingedly connected with the other unit for swinging movements to open and closed positions relative to said other unit; a composite device providing a groove, said device having two rolls, said two rolls, when in operative position, being axially spaced with their adjacent end faces providing walls of said groove, each of said two rolls having a rolling surface facing said main roll when said two rolls are in operative position, said device being thereby

adapted for continuous rolling engagement with the inner surface of said bloom, with said groove adjacent thereto, one of said two rolls being carried by one of said frame units and the other of said two rolls being carried by the other of said frame units whereby, when said swinging unit is in open position, blooms may be inserted and removed, and when said swinging unit is in closed position said two rolls will be in operative position; means for effecting relative movement of said carriage and said main roll to thereby vary the distance between said rolling surfaces and the said main roll; means cooperating to support said bloom with its outer surface adjacent said main roll and its inner surface adjacent said two rolls and said groove; controllable means carried by said carriage for effecting relative movement of said two rolls to thereby vary the width of said groove whereby, by control of said relative movement of said two rolls, material of said bloom can be shaped within said groove to form an annular web of predetermined width on said inner surface of said bloom; and means carried by said carriage for locking said swinging frame unit in closed position.

16. A rolling mill for rolling a metal annular bloom, comprising a main roll adapted for operation upon the outer surface of said bloom; a movable carriage adjacent said main roll including a frame having two spaced parts and a third part connecting said two spaced parts providing an open space between the three said parts; a composite rolling device carried by said carriage, providing a groove when in operative rolling position, said device being disposed across said space and connected to said two spaced parts, and having two axially spaced rolls, the adjacent end faces of said two rolls providing walls of said groove, each of said two rolls having a rolling surface facing said main roll, said device being thereby adapted for continuous rolling engagement with the inner surface of said bloom, with said groove adjacent thereto, one of said two rolls being carried by one of said two spaced parts and the other of said two rolls being carried by the other of said two spaced parts; power means for effecting relative movement of said carriage and said main roll to thereby vary the distance between said rolling surfaces and said main roll; means cooperating to support said bloom with its outer surface adjacent said main roll and its inner surface adjacent said two rolls and said groove; controllable means carried by said carriage for effecting relative movement of said two rolls to thereby vary the width of said groove whereby, by control of said relative movement of said two rolls, material of said bloom can be shaped within said groove to form an annular web of predetermined width on said inner surface of said bloom; and means for relatively moving said two rolls from operative rolling position to sufficiently spaced relation to provide a clear, free space between said adjacent end faces thereof to permit the passage through said free space of a bloom both to and from operative position.

17. A rolling mill for rolling a metal annular bloom, comprising a frame having two spaced parts and a third part connecting said two spaced parts providing an open space between the three said parts; a composite rolling device providing a groove when in operative rolling position, said device being disposed across said space and connected to said two spaced parts, and having two axially spaced rolls, the adjacent end faces of

said rolls normally forming walls of said groove, said rolls being adapted for rolling the inner surface of said bloom, one of said rolls being carried by one of said two spaced parts and the other of said rolls being carried by the other of said two spaced parts; means for supporting said bloom with said inner surface adjacent said groove and rolls; means for moving said rolls to adjust the position of said groove axially of said bloom whereby, during the operation of said mill, an annular web of predetermined axial position can be formed on said inner surface of said bloom; and means for relatively moving said rolls from operative rolling position to sufficiently spaced relation to provide a clear, free space between said adjacent end faces thereof to permit the passage through said free space of a bloom both to and from operative position.

18. A rolling mill for rolling a metal annular bloom, comprising a pair of cylindrical rolls having adjacent ends spaced to provide a groove therebetween, the cylindrical faces of said rolls being adapted to roll the inner surface of said bloom, and said groove being adapted to form a web on said inner surface; supporting means for supporting said bloom with said cylindrical faces and said groove adjacent said inner surface of said bloom; and separate means for independently moving each of said rolls relative to said supporting means for effecting axial adjustment of said groove relative to said inner surface of said bloom whereby, during the operation of said mill, an annular web of predetermined axial position can be formed on said inner surface of said bloom.

19. A rolling mill for rolling a metal annular bloom, comprising a pair of cylindrical rolls having adjacent ends spaced to provide a groove therebetween, the cylindrical faces of said rolls being adapted to roll the inner surface of said bloom, and said groove being adapted to form a web on said inner surface; an arbor adapted to form the inner wall of said web, said arbor extending from the inner end of one of said rolls, and across the space between said adjacent ends; supporting means for supporting said bloom with said cylindrical faces and said groove adjacent said inner surface of said bloom; and separate means for independently moving each of said rolls relative to said supporting means for effecting axial adjustment of said groove relative to said inner surface of said bloom whereby, during the operation of said mill, an annular web of predetermined axial position can be formed on said inner surface of said bloom.

20. A rolling mill for rolling a metal annular bloom, comprising a pair of rolls having adjacent end faces spaced to provide a groove therebetween, and rolling faces for rolling the inner face of said bloom, said groove being adapted to form a web on said inner face; a roll for rolling the outer circumferential face of said bloom; means for supporting said bloom with its inner face adjacent said pair of rolls and groove and with its outer face adjacent said roll; and separate controllable means, one of said separate means operable for varying the distance between said pair of rolls and said roll and another of said separate means operable for varying the space between the rolls of said pair of rolls, whereby a ring of predetermined radial thickness and a web of predetermined axial thickness can be formed from said bloom.

21. A rolling mill for rolling a metal annular bloom, comprising a pair of rolls having adjacent

end faces spaced to provide a groove therebetween, and rolling faces for rolling the inner face of said bloom, said groove being adapted to form a web on said inner face; a roll for rolling the outer circumferential face of said bloom; rolls 5 for rolling the end faces of said bloom; means cooperating to support said bloom between said end face rolling rolls, with its inner face adjacent said pair of rolls and groove and with its outer face adjacent said roll; and separate controllable means, one of said separate means operable for varying the distance between said pair

of rolls and said roll, another of said separate means operable for varying the space between the rolls of said pair of rolls, and another of said separate means operable to vary the distance between said end face rolling rolls, whereby a ring 5 of predetermined radial thickness and axial width and a web of predetermined axial thickness can be formed from said bloom.
